UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

APPARATUS FOR TREATING OIL.

Continuation of application Serial No. 420,871, filed November 1, 1920. This application filed May 7, 1925. Serial No. 28,726.

This application is a continuation of my application, Serial No. 420,871, filed November 1, 1920.

This invention relates to improvements in apparatus for treating oil and refers more particularly to an apparatus for pressure distillation in which the oil is treated in a battery of stills, any number of which stills may be in operation or on stream at any given time. In the present invention, the oil is distilled under a predetermined pressure and the vapors condensed under a regulated reduced pressure, the whole process being carried out during both distillation and condensation under the pressure of the generated vapors.

In the present invention, the vapor lines of the stills are all connected to a common reflux condenser consisting of a pair of main headers between which is interposed a plurality of aerials, any one or more of which may be cut out of operation. The uncondensed vapors pass from the delivery header of the reflux condenser to a final condenser and thence to a main receiver. The pressure can be regulated from the outlet side of the receiver. The reflux condensate is also continuously returned to the stills for further treatment.

30 In the drawings:

Fig. 1 is a view partly in section and partly in side elevation of my improved apparatus.

Fig. 2 is a top plan view of the same.

These views are somewhat diagrammatic. Referring in detail to the drawings, 1, 2, 3, 4 and 5 designate a battery of stills (from five to twenty stills or more may constitute a battery). These stills are mounted in suitable furnaces whereby they may be preferably independently heated. Each still is provided with a residue drawoff pipe 6, having a throttle valve 7, and a pressure gauge 8. Oil is introduced into the stills by means of a pump 9, the inlet side of which is connected to a pipe 10 having valve 11 to any suitable source of raw oil supply. The discharge side of the pump is connected to a line 12, leading to a delivery header 13. This delivery header 13 is provided with a plurality of branches 14, each having a throttle valve 15. Each branch 14 is provided with an extension 16 extending into each still near the lower end of the latter,

this extension 16 being perforated as shown at 17, in order to discharge the fresh oil through these perforations along the entire length of the still. The arrangement is such that by suitably regulating the valves 15, fresh oil may be fed to any one or more of the stills. Each still is provided with a vapor outlet pipe 18, connecting to the lower end of a header 19. This header 19 is provided with pressure gauge 20 and its lower end is provided with a reflux condensate drawoff pipe 21 having throttle valve 22, which pipe 21 is connected to the suction side of the pump 9. Each pipe 18 is provided with a throttle valve 23, by which the pipe may be entirely closed and with automatic reducing valve 24 and check-valve 25, the latter tending only to permit the vapors to pass into the header 19 but closing against pressure from the header 19. (In certain cases hereinafter referred to, these check-valves 25 may be taken out of the pipes 18.) The header 19 is connected to a plurality of upwardly inclined aerial condenser pipes 26, the upper ends of these pipes 26 being in turn connected to the bottom of a second header 27. Throttle valves 28 and 29 are interposed in either end of each pipe 26 whereby any given pipe may be cut out of the system in the event there is an excess of aerial condensing surface. The upper end of the header 27 is connected by vapor line 30 having throttle valve 31 to the top of condenser coil 32, seated in condenser box 33. The lower end of this coil 32 is connected by pipe 34 to the top of receiver 35. This receiver 35 is provided with pressure gauge 36, liquid level gauge 37, distillate drawoff pipe 38, controlled by throttle valve 39 and gas outlet pipe 40 controlled by throttle valve 41.

The process may be operated as follows: We will assume that stills 1, 2 and 3 of the battery are charged with Oklahoma gas oil of say, 31 degs. Baumé gravity, the valves 23 closed and the stills charged from one half to two thirds full with said gas oil and the stills heated until an oil temperature of 700 to 750 degs. F. has been reached and the stills are under a vapor pressure of 135 pounds. The valves 23 are then opened and the vapors permitted to pass through the condensing part of the apparatus. The pressure will then be regulated by means of the

valves on the receiver. (In this case, I will dispense with the check valves 25.) The automatic reducing valves 24 are so set as to maintain a difference in pressure of say, 5 10 pounds; while the pressure on the still is 135 pounds, the pressure on the condensing part of the apparatus is 125 pounds. Inasmuch as only part of the battery is now in operation, the remainder of the stills are cut 15 out of the system by closing the proper valves. There will now probably be an excess of aerial surface, so a plurality of pipes 26 are cut out of the reflux condenser by closing their corresponding valves 28 and 29. As the vapors pass out the inclined aerial lines 26, the heavier fractions thereof will condense and be returned to the bottom header 19 by gravity and thence delivered by means of the pipe 21 to the feed pump 9. 20 By means of the valve 22, the flow of the condensate to the pump may be regulated. Fresh oil may be continuously fed in regulated quantities to the stills of the battery which are in use, and the residue constantly 25 drawn off. In this way, the process may be continuous. If desired, the charging stock may be fed intermittently or the process may be operated as a batch process.

In case the process is operated as a batch 30 process, after the stills in use are charged, the valve 11 will be shut. The reflux condensate can be continuously returned to the stills then on stream and recracked.

As another way of operating the apparatus and process, it may be operated as a 35 batch process and the reflux condensate returned to stills 4 and 5 of the battery and there heated to any temperature desired, which temperature might for example be 800 40 to 850 degrees F., as this reflux condensate mixed with many oils is more difficult to crack than is the raw charging stock. Where the process is operated in this manner, the branches leading from the feed header 13 to 45 the stills 1, 2 and 3 are cut out of the system by closing the valves 15.

I have stated that in operating the process in accordance with the methods above described, the check valves 25 may be eliminated. The process may be operated by 50 leaving these valves in and operating the apparatus as before. The apparatus may also be operated in substantially the manner previously described in detail except that the 55 reducing valves 24 may be taken out or bypassed in a suitable manner (unnecessary here to show) in which case, the whole system may operate under the same pressure of say, 135 pounds. Where the check-valves are 60 used, of course, no incondensable gas can flow back into the stills. Also where the automatic reducing valves are used, they may be so adjusted that substantially no incondensable gas can flow by them back into the 65 stills.

It is to be understood that all the stills of the battery may be used at the same time but they should be preferably kept out of the system until they are ready to go on stream or otherwise produce a substantially 70 normal hourly yield of the desired pressure distillate. By means of the processes above described, over 50% of the gas oil may be converted into pressure distillate having a Baumé gravity of from 51 to 54 degs. 75

I claim as my invention:

1. In an apparatus for cracking oil, the combination with a battery of stills, of a reflux condenser comprising a pair of main headers, aerial pipes interposed therebetween, connections between one header and the vapor space of each still, connections between the other header and a final condenser, means for cutting out of the system one or more aerial pipes, pressure regulating valves 80 interposed between the stills and the header connected to the vapor space of said stills, means for drawing off reflux condensate from one of said headers, and means for returning said reflux condensate to any of said 85 stills.

2. In an apparatus for cracking oil, the combination with a battery of stills, of a reflux condenser comprising a pair of main headers, aerial pipes interposed therebetween, connections between one header and the vapor space of each still, connections between the other header and a final condenser, pressure regulating valves 95 interposed between the stills and the header connected to the vapor space of said stills, means for drawing off reflux condensate from one of said headers, and means for returning said reflux condensate to any of said 100 stills.

3. In an apparatus for cracking oil, the combination with a battery of stills, of a reflux condenser comprising a pair of main headers, aerial pipes interposed therebetween, connections between one header and the vapor space of each still, connections 105 between the other header and a final condenser, means for drawing off reflux condensate from one of said headers, and means for returning said reflux condensate to any 110 of said stills.

4. In an apparatus for cracking oil, the combination with a battery of stills, of a reflux condenser comprising a pair of main headers, aerial pipes interposed therebetween, connections between one header and the vapor space of each still, connections 115 between the other header and a final condenser, means for cutting out of the system one or more aerial pipes, pressure regulating valves 120 interposed between the stills and the header connected to the vapor space of said stills.

5. In an apparatus for cracking oil, the combination with a battery of stills, of a reflux condenser comprising a plurality of 125

main headers, aerial pipes interposed therebetween, connections between one of said headers and the vapor space of each still, connections between another of said headers and a final condenser, means for cutting out of the system one or more aerial pipes, comprising valves located respectively at each end of each aerial pipe and adjacent the main headers, pressure regulating valves interposed between the stills, and the header connected to the vapor space of said stills.

6. In an apparatus for cracking oil, the combination with a battery of stills, of a

reflux condenser comprising a pair of main headers, aerial pipes interposed therebetween, connections between one header and the vapor space of each still, connections between the other header and a final condenser, means for cutting out of the system one or more stills, and means for cutting out of the system one or more aerial pipes, pressure regulating valves interposed between the stills and the header connected to the vapor space of said stills.

CARBON P. DUBBS.
